US0D1097505S

(12) United States Design Patent (10) Patent No.: US D1,097,505 S
(45) Date of Patent: * Oct. 14, 2025

(54) SHOE

(71) Applicant: Converse Inc., Boston, MA (US)

(72) Inventor: Tony Devito, Cambridge, MA (US)

(73) Assignee: Converse Inc., Boston, MA (US)

() Term: 15 Years

(21) Appl. No.: 29/924,543

(22) Filed: Jan. 19, 2024

(51) LOC (15) Cl. 02-04

(52) U.S. Cl.

USPC D2/969

(58) Field of Classification Search

USPC D2/902-908, 946, 947, 969-978

CPC A43B 1/04; A43B 1/05; A43B 3/10; A43B 3/12; A43B 3/14; A43B 3/122; A43B 3/126; A43B 3/0036; A43B 5/06; A43B 5/10

(57) CLAIM

The ornamental design for a shoe as shown and described.

DESCRIPTION

FIG. 1 is a front perspective view of a shoe showing my new design;

FIG. 2 is a side view thereof;

FIG. 3 is a rear perspective view thereof;

FIG. 4 is a rear view thereof;

FIG. 5 is an opposite side rear perspective view thereof;

FIG. 6 is an opposite side view thereof; and,

FIG. 7 is an opposite side front perspective view thereof. The uneven-length broken lines showing the buckle region form no part of the claimed design. The even-length circular broken lines represent holes which form no part of the claimed design. The even-length elongated broken lines within the shaded area represent stitching that forms no part of the claimed design. The uneven-length broken lines depicting the remainder of the shoe form no part of the claimed design.

1 Claim, 7 Drawing Sheets
